UNITED STATES PATENT OFFICE.

HENRY A. WAHLERT, OF ST. LOUIS, MISSOURI, ASSIGNOR TO THE ACME PIPE CLAMP COMPANY, OF ILLINOIS.

DESIGN FOR A PIPE-CLAMP MEMBER.

SPECIFICATION forming part of Design No. 30,538, dated April 11, 1899.

Application filed September 14, 1897. Serial No. 651,690. Term of patent 14 years.

To all whom it may concern:

Be it known that I, HENRY A. WAHLERT, a citizen of the United States, residing at St. Louis, in the State of Missouri, have invented and produced a new and original Design for a Pipe-Clamp Member, of which the following, taken in connection with the accompanying drawings, is a full and exact description.

The drawings, Figures 1 and 2, show different views of a pipe-clamp member having the form or configuration which embodies my design, Fig. 1 being an exterior perspective view or view of the convex ribbed surface, and Fig. 2 an interior view or view of the concave plain surface.

The design relates to pipe-clamps composed of a plurality of members which are counterparts, and the individual member embraced by the design has the form or configuration of a longitudinal section of a tapered hollow cylinder smooth on its interior or concave face, as at *a*, and ribbed on its exterior,

as at *b*, said ribs arranged at an incline to the longitudinal axis of the member or having the appearance of portions of spiral threads. The thickest end of the tapered section has on its convex face a flange *c*, bounded by the straight and intersecting faces *d d*, and on its concave face at points corresponding with said flange (or base of the section) an indentation *e* at one side and on the opposite side a correspondingly-shaped projection *f*.

Having thus particularly pointed out the shape or configuration of my design, I claim—

The design for a pipe-clamp member as herein shown and described.

In testimony whereof I have hereunto attached my signature in the presence of two witnesses.

HENRY A. WAHLERT.
